Primary Examiner — Ian Simmons*Assistant Examiner* — Shannon Weekley(74) *Attorney, Agent, or Firm* — Howson & Howson LLP(57) **CLAIM**

The ornamental design for a cutter for making cake decorations from sheets of icing, as shown and described.

DESCRIPTION

FIG. 1 is a top, right perspective view of the cutter for making cake decorations from sheets of icing, showing our new design;

FIG. 2 is a top plan view thereof;

FIG. 3 is a bottom plan view thereof;

FIG. 4 is a rear elevational view thereof;

FIG. 5 is a front elevational view thereof; and

FIG. 6 is a left side elevational view, the right side elevation being a mirror image, thereof; and,

FIG. 7 is a bottom, left perspective view thereof.

The right side elevational view is a mirror image of the right side elevational view.
